UNITED STATES PATENT OFFICE.

MABEL H. SLATER, OF NEW YORK, N. Y.

DOLL.

Application filed February 23, 1924. Serial No. 694,504.

To all whom it may concern:

Be it known that I, MABEL H. SLATER, a citizen of the United States, residing at New York, in the county of New York and State of New York, have invented new and useful Improvements in Dolls, of which the following is a specification.

This invention relates to an improved rag doll and especially relates to the eye portion 10 of said doll, the object of the invention being to provide an article which can be sewed or otherwise attached to the cloth forming the face of a rag doll in the rear of the eye openings in said face and representing an eye.

The device of this invention has further for its object to provide an article of the character set forth in which the iris of the eye is shiftably mounted in the chamber 20 provided in the receptacle fast to the face portion of the doll at the rear of the eye opening so that a disc-shaped iris contained in said receptacle may be shifted to assume different positions relatively to the opening.

A pair of receptacles are provided for the two eyes of the doll so that as the iris shaped discs are shifted into different positions relatively to their respective openings, 30 very comical effects may be produced.

The invention consists in an article of manufacture such as hereinafter described and set forth in the claims, and in a rag doll to which said article of manufacture 35 is attached.

Referring to the drawings:

Figure 1 is a front elevation of the head and neck portion of a rag doll.

Fig. 2 is an enlarged front elevation of 40 the eye portions of said doll.

Fig. 3 is a sectional elevation taken on the line 3-3 of Fig. 2.

Like numerals refer to like parts throughout the several views of the drawings.

In the drawings, 5 is the head of the doll made in a manner well known to those skilled in the art, and stuffed with cotton. 6 is the face portion. 7 are slits in the material 8 of the face portion 6, representing eye 45 openings. A strip of celluloid 9 is fastened by stitches 10 to the material 8, the stitches projecting through the material and representing eye lashes 11. A saucer-shaped receptacle 12 consisting of a body portion 13 and flange 14 is attached by adhesive material 50 to the strip of celluloid 9, as illustrated

in Fig. 3, said receptacle 12 being provided with a chamber 15 in which is shiftably positioned a disc-shaped member 16 representing the iris of the eye. The strip of celluloid 9 is preferably of sufficient length to enable two of the saucer-shaped receptacles to be attached thereto as illustrated in Fig. 2. The head of the doll is stuffed in the usual manner with cotton 17 and before the cotton head for the rag doll is sewed together, the strip of transparent celluloid 9 is attached on the wrong side of the material 8 forming the face portion of the doll. The celluloid prevents the iris from falling out while allowing the same to be seen through the eye opening 7, thus making the toy safe for a child as the eyes cannot be detached and swallowed. The opaque saucer-shaped receptacles 12 are 75 glued to the celluloid and the chambers 15 therein are decidedly larger than the iris so that when the iris is rolled around to the edge of the receptacle, it is nearly concealed from view through the eye openings. 80

In use, when the doll is tipped into different positions the irises assume different positions relatively to the eye opening 7. The inner face of the receptacle 12 is tinted 85 to represent the white of the eyeball.

It is evident that while I have described my invention as particularly adapted to a rag doll, I do not wish to be limited to that particular use of the invention, as the eye member may be attached not only to 90 dolls of different kinds, but also may be used in connection with toy animals, or birds of different kinds, or in connection with any supporting member, the supporting member in the present case being illustrated as a doll's head.

I claim:

1. A rag doll provided with a slit in the face portion thereof representing an eye opening, transparent material attached thereto and extending across the rear of said opening, a receptacle provided with a chamber and fastened to said doll and having an opening in its front face in alignment with the eye opening and an iris member shiftably positioned in said chamber and visible through said opening. 100

2. A rag doll provided with a split in the face portion thereof representing an eye opening, a piece of celluloid extending 110 across the rear of said opening, a receptacle provided with a chamber and fastened to

- said doll and having an opening in its front face in alignment with the eye opening and an iris member shiftably positioned in said chamber and visible through said opening.
5. 3. A rag doll provided with a slit in the face portion thereof representing an eye opening, a piece of transparent material attached thereto and extending across the rear of said opening, a saucer-shaped receptacle fast to said transparent material providing a chamber in alignment with said opening and an iris member shiftably positioned in said chamber and visible through said opening.
10. 4. A rag doll provided with a slit in the face portion thereof representing an eye opening, celluloid positioned at the rear of said opening, stitches fastening said celluloid to said face portion and projecting therethrough adjacent to the eye opening and representing eye lashes, a receptacle provided with a chamber fastened to the reverse face of said celluloid and having an opening in its front face in alignment with
15. the eye opening and an iris member shiftably positioned in said chamber and visible through said opening.
20. 5. As an article of manufacture, an eye member for dolls comprising a receptacle provided with a chamber opening through one face thereof, an iris member shiftably positioned in said chamber and a piece of
25. transparent material extending across said chamber opening and adapted to be fastened to the face portion of a doll in alignment with an eye opening in said face portion.
30. 6. As an article of manufacture, an eye member for dolls comprising a receptacle provided with a chamber opening through one face thereof, the inner face of the receptacle chamber being colored to represent an eyeball, an iris member shiftably positioned in said chamber and a piece of transparent material extending across said chamber opening and adapted to be fastened to the face portion of a doll in alignment with an eye opening in said face portion.
35. 7. As an article of manufacture, a supporting member provided with an opening, a transparent member extending across said opening, a saucer-shaped receptacle fast to said transparent member and provided with a chamber in alignment with said opening, and an iris member shiftably positioned in said chamber and visible through said opening.
40. In testimony whereof I have hereunto set my hand in presence of two subscribing witnesses.
50. MABEL H. SLATER.
55. Witnesses:
SISTER MINNA SCHRAGE,
WILLIAM LANCASTER.
